UNITED STATES PATENT OFFICE.

SILAS G. RANDALL, OF MIDDLEBURY, VERMONT.

KEEPING AIR-SPRINGS SUPPLIED WITH AIR.

Specification of Letters Patent No. 23,497, dated April 5, 1859.

To all whom it may concern:

Be it known that I, SILAS G. RANDALL, of Middlebury, in the county of Addison and State of Vermont, have invented a new and useful manner of supplying air-springs with air when said springs are applied to cars, carriages, or other locomotive machines requiring them; and I do hereby declare the following to be a full, clear, and exact description of the same, reference being had to the accompanying drawings, making a part of this specification, in which—

Figure 1, represents a side view of a common truck such as are used with cars, and Fig. 2, represents a transverse section through the air springs, and their communicating parts.

Similar letters of reference where they occur in the separate figures denote like parts in both of them.

The use of air springs on cars, carriages, &c., has been practically abandoned, from the difficulty in keeping them supplied with air, or preventing their leaking. I do not propose to make air springs proof against losing their confined air, as this is found to be impracticable under the heavy and varying pressure that comes upon them, but I overcome this evil, by forcing a supply into the springs during the entire period that the car or carriage is in motion, so that the springs are constantly effective when in use, whatever may be the leakage from wear, or sudden jars or pressure.

My invention consists in so connecting an air pump or pumps to the air springs of cars, carriages, &c., and further attaching the piston or pistons of said pumps to the running gear, or other moving part thereof, as that when said car or carriage is in motion, the air pump or pumps shall be constantly furnishing air to take the place of that lost by leakage.

To enable others skilled in the art to make and use my invention I will proceed to describe the same with reference to the drawings.

A, represents a truck frame, and B, the wheels supporting it. On a cross plate a, extending from one side to the other of said truck frame, I arrange two air springs which may be composed substantially of metallic cylinders b, b, with pistons c, c, fitting snugly therein by packing or otherwise, so that they may rise and fall therein. To each of these pistons, are attached rods

d, d, which support the bolster C, on which one end of the car body rests.

e, is an air pipe or tube which connects with the air chambers of each spring so that one pump may supply both with air, though if found preferable each spring may have its own pump or one air pump may supply the springs of an entire train. An air pump on the locomotive to supply an entire train of cars may also be used, the only objection to such use being because it would involve the trouble of making elastic air tight connections between the cars and locomotive.

f, is an ordinary air pump, and i, a piston working in it.

n, is a connecting rod, connecting the piston i to a wrist pin on one of the wheels, or to a crank or eccentric on the axle, so as to reciprocate said piston i, in the pump. A valve 5, covers an opening leading from the pump, to the chamber under the piston c, by which said chamber is filled with air; and the opposite spring is supplied through the pipe e. An opening 6 is made through the piston of the opposite spring from the pump said opening being covered by a safety valve or spring 7, so that any excess of air over a given density may escape.

The air enters the air pump through an opening or seat that has a valve 2, snugly fitting it, said valve having attached to it, a valve rod 3, and a spring 4, to close it after the air has opened it and rushed in to fill the vacuum created by the drawing forward of the piston i. When the piston i, is making the stroke that forces air into the springs the valve 2, is driven tight to its seat, and the air in the pump driven up through the opening covered by the valve 5, and so on.

Having thus fully described the nature and object of my invention, what I claim therein as new and desire to secure by Letters Patent, is—

So combining an air spring, and an air pump, or its equivalent, with a car, carriage, or other moving conveyance, as that the motion of said car, carriage, or other conveyance shall through such air supplier, keep the air springs supplied with air, substantially as herein set forth.

SILAS G. RANDALL.
